HANDLE FOR MANUAL TOOLS SUCH AS SCREW
DRIVERS OR THE LIKE

Raymond G. Knudsen and Robert E. Badger, Kenosha, Wis., and Peter Langmack, Brooklyn, N.Y., assignors to Snap-On Tools Corporation, Kenosha, Wis., a corporation of Delaware

Filed June 7, 1961, Ser. No. 65,505

Term of patent 14 years

(Cl. D93—4)

FIGURE 1 is a perspective view of a handle for manual tools such as screw drivers or the like showing our new design;

FIGURE 2 is a side elevational view thereof; and
FIGURE 3 is an end view thereof.

We claim:

The ornamental design for a handle for manual tools such as screw drivers or the like, substantially as shown.
